[57] CLAIM

The ornamental design for a double lumen catheter, as shown and described.

DESCRIPTION

FIG. 1 is a side elevational view of a double lumen catheter showing my new design;

FIG. 2 is a rear elevation view of the catheter illustrated in FIG. 1;

FIG. 3 is an end view of the solid line portion of the catheter illustrated in FIG. 1 as seen along line 3—3 thereof;

FIG. 4 is a sectional view of the catheter illustrated in FIG. 1 as taken along line 4—4 thereof;

FIG. 5 is an end view partly in section of the catheter illustrated in FIG. 1 as seen along line 5—5 thereof; and FIG. 6 is a sectional view of the bottom portion of the catheter illustrated in FIG. 2 as taken along line 6—6 thereof.
